UNITED STATES PATENT OFFICE.

CARL R. KOSITZKY, OF BISMARCK, NORTH DAKOTA.

FASTENING DEVICE.

1,218,189.

Specification of Letters Patent.

Patented Mar. 6, 1917.

Application filed October 1, 1914. Serial No. 864,486.

To all whom it may concern:

Be it known that I, CARL R. KOSITZKY, a citizen of the United States of America, residing at Bismarck, in the county of Burleigh and State of North Dakota, have invented certain new and useful Improvements in Fastening Devices, of which the following is a specification, reference being had therein to the accompanying drawing.

10 This invention relates to fastening devices and has special reference to a fastener which is constructed so as to releasably connect the two ends of a band together so as to hold the band in a releasable assembled 15 condition.

Another object of this invention is the production of a fastening device which is adapted to be particularly used upon knock-down crates so as to hold the same in a set 20 up position when desired.

Another object of this invention is the production of a fastening device which comprises a plate having a substantially S-shaped tongue formed thereon, which tongue 25 is adapted to extend through an opening in one end of the band for releasably holding the two ends of the band in engagement with each other.

With these and other objects in view this 30 invention consists of certain novel combinations, constructions, and arrangements of parts as will be hereinafter fully described and claimed.

In the accompanying drawings:—

35 Figure 1 is a central vertical section through the crate, showing the same in an assembled position by means of the fastening device.

Fig. 2 is a horizontal section through one 40 of the connecting bands showing the manner in which the fastening device is used.

Fig. 3 is a detail perspective view, partly 45 broken away, of the connecting bands of a crate, showing the fastening device in operation thereon.

Referring to the accompanying drawings by numerals it will be seen that the fastening device is adapted to be used upon a crate, having a top band 3 and a bottom band 4. 50 These bands 3 and 4 are connected by vertically extending metal slats 9, as shown in Fig. 1.

Each band 3 and 4 is provided with

rolled edges 11 for efficiently reinforcing the same around their respective edges. The 55 metallic plate 12 is secured to one end of each semi-circular band, and the substantially S-shaped tongue 13 formed of spring metal extending therethrough constitutes a locking pocket 14 and an inwardly bent 60 spring lip 15. Each plate 12 is secured to the bands 3 and 4 by means of the rivets 16.

The bands 3 and 4 are also provided adjacent their free ends with apertures 17 through which apertures the substantially 65 S-shaped tongues are adapted to pass for holding the ends of the bands in engagement with each other. At this time the ends of the bands will fit within the pockets 14 of the tongues 13 for holding the crate upon 70 which the device is to be used from being accidentally collapsed. By having the lip 15 of each tongue formed of spring metal it will be seen that the lip will assist in retaining the tongue in its correct position upon 75 the free end of the bands for the free end of the lip will bear upon the bands for urging the body of the tongue in one direction for holding the tongue from accidentally 80 springing through the opening or aperture 85 of the band.

From the foregoing description it will be seen that a very simple and efficient fastening device has been provided for releasably retaining the two ends of the band in engagement with each other; whereby a knock down crate may be efficiently retained in a set up position. It will further be seen that owing to the S-shaped construction of the tongue, the body thereof extending rearwardly from the plate 12 will form a pocket in which the free end of the band will fit, while the forwardly extending lip will bear upon the free end of the band and will thus cause the body to be urged into engagement 90 with the free end of the band, thus holding the tongue from accidentally releasing the ends of the band.

What I claim is:—

A fastening device for metallic knock-down shipping crates comprising an elongated plate, said plate being adapted to be secured upon a band, a substantially S-shaped resilient tongue formed upon one end of said plate and extending to one side 105 thereof, said tongue comprising a rear-

wardly extending body terminating in a forwardly extending lip, said tongue being adapted to pass through an aperture of the band, whereby the body of said tongue will 5 embrace the inner portions of the band for holding the band ends together, and said spring lip being adapted to bear upon the band for urging the body in one direction

for holding said tongue from accidentally springing through the opening of the band. 10

In testimony whereof I hereunto affix my signature in presence of two witnesses.

CARL R. KOSITZKY.
